UNITED STATES PATENT OFFICE.

FRANK J. FENCL, OF CHICAGO, ILLINOIS.

CIRCUIT BREAKER.

Application filed March 26, 1925. Serial No. 18,353.

The invention relates to circuit breakers and more particularly to those circuit breakers which are operated by clocks.

One object of the invention is to provide a clock operated circuit breaker of new and improved construction in which provision is made for rapidly opening a circuit so that arcing or fusing of the switch contacts is eliminated.

Another object of the invention is to provide a circuit breaker which is simple in construction and may be produced at a low cost.

The invention consists in the several novel features hereinafter set forth and more particularly defined by the claims at the conclusion hereof.

In the drawing: Fig. 1 is a front view of a clock embodying the invention. Fig. 2 is a side elevation of the new and improved circuit breaker and the clock mechanism adapted to operate same. Fig. 3 is a side elevation of the invention, showing it in its operative position. Fig. 4 is a front view of the parts shown in Fig. 2. Fig. 5 is a perspective of one of the leaf springs used in actuating the circuit breaker. Fig. 6 is a detail perspective of the pivot member and portions of the parts associated therewith. Fig. 7 is a perspective of the pivot member.

The invention is exemplified with a clock comprising the usual enclosing housing 10 within which is a frame-work 11 for supporting the various clock trains and mechanism as well understood in the art. The new and improved circuit breaker is disposed within the clock housing 10 and comprises a pair of arm or lever members 12 formed from sheet metal and centrally pivoted by pin and slot connections 13, 13', to a pair of supports 14 which also are formed from sheet metal and are secured or riveted, as at 15, to the framework 11. The inner ends of lever members 12 are pivoted, as at 16, to a pivot member 17. Disposed between said pivot member 17 and the supports 14 are a pair of leaf springs 18, the inner ends of which are notched, as at 19, to interfit with notches 20 formed in the pivot member 17, as shown in Fig. 6. The outer ends of springs 18 are notched, as at 21, and are adapted to interfit with notches 22 formed in the supports 14, so that the springs will be securely held against displacement. The springs 18 are normally under

tension and are disposed in such a manner that when the arm members 12 are in dead center position, as shown in Fig. 2, no pressure is exerted to change or alter the position of the arm members. When the arm members 12 are moved out of their dead center position, the springs 18 will tend to expand and cause the inner ends of the arm members to rapidly move inwardly. The inner ends of said arm members are so formed

that they abut against each other while in their dead center position in such a manner that outward movement of the arm members is prevented. The outer end of one of the arm members 12 is provided with an extension 12^a which is adapted to form a switch contact, which, when the arm members are in the position shown in Fig. 2, will abut against a spring contact 24 to close any suitable circuit, such as a radio or alarm circuit. Contact 24 is secured to the framework 11 and insulated therefrom by suitable insulating material 24^a. When the arm members are actuated by the springs 18, their movement will be so rapid that no arcing or fusing of the contacts 12^a and 24 will occur.

The outer end of the other arm member 12 is extended to form a portion 12^b which is adapted to be actuated to move the inner ends of the arm 12 inwardly and out of their dead center position. The mechanism for actuating portion 12^b comprises a gear 25 disposed adjacent said portion and mounted on a shaft 26 which is journaled in the framework 11, and a gear 27, meshing with gear 25 and rotatably mounted on a shaft 28, journaled in said framework and adapted to be driven by the clock train and mechanism. Shaft 26 is provided at its rear end with a knurled head 29 so that it may be manually rotated. The outer end of said shaft extends through the time dial 31 of the clock and is provided with an index pointer 32 which is adapted to indicate on a dial 33.

A pin 34 is secured to shaft 26 adjacent gear 25 and is adapted to engage a collar 35 on said gear. Gear 25 is pressed outwardly by a spring 36 so that the collar 35 will engage pin 34 at all times. The collar is provided with a notch 37, so that when the pin registers therewith, gear 25 will be shifted outwardly by spring 36 against the portion 12^b of the arm member 12 to actuate the circuit breaker and cause the circuit between the contacts 12^a and 24 to be broken. A shaft

38 is slidably mounted in the framework 11 and is provided with a pair of arms 39, adapted to straddle portion 12^a. By pulling shaft 38 rearwardly, the circuit breaker may 5 be set into its dead-center and inoperative position.

In practice, a conductor 40, connected to a radio receiving circuit or the like, will be connected to contact 24 and a return conductor 41 will be connected to the framework 11. Shaft 38 will be pulled outwardly, thereby placing the circuit breaker in its inoperative and dead center position. Shaft 26 will then be rotated to adjust the index 10 pointer 32 and set the period at which time the circuit is to be broken. When the predetermined time is reached, pin 34 will come 15 into registration with the notch 37 and gear 25 will be pressed outwardly by spring 36 against the portion 12^b on one of the arm 20 members 12, thereby causing the members 12 to be moved inwardly and out of their dead center position, whereupon springs 18 will cause a rapid inward movement of the members 12 and the portion or contact 12^a will 25 become disengaged from the contact 24 and the circuit broken.

The invention exemplifies a new and improved circuit breaker which is simple in 30 construction and which may be produced at a low cost.

The invention is not to be understood as 35 restricted to the details set forth, since these may be modified within the scope of the appended claims, without departing from the spirit and scope of the invention.

Having thus described the invention, what I claim as new and desire to secure by Letters Patent, is:

40 1. A circuit breaker comprising a pair of supporting members, a pair of arms pivoted to said members by pin and slot connections, a member pivotally connected to the inner ends of said arms, means for preventing the 45 arms from moving in one direction past their substantially dead-center position, leaf springs between the supporting members and said member for shifting said arms and member in the opposite direction after the

arms have been moved out of said position, 50 and switch means controlled by one of said arms.

2. A circuit breaker comprising a pair of supporting members, a pair of arms pivoted to said members by pin and slot connections, 55 a member pivoted to the inner ends of said arms, said arms being provided at their inner ends with abutting surfaces for preventing them from moving in one direction past their substantially dead-center position, leaf 60 springs between the supports and said member in the opposite direction for shifting the arms and member after the arms have been moved out of said position, and switch means controlled by one of said arms. 65

3. A circuit breaker comprising a pair of supporting members, a pair of arms centrally pivoted to said members by pin and slot connections, a member pivotally connected to the inner ends of said arms, means 70 for preventing outward movement of said arms beyond their substantially dead-center position, springs between the supporting members and said member for shifting the arms and member inwardly after the arms 75 have been moved out of said position, and switch means controlled by the outer end of one of said arms.

4. In combination with a clock comprising a frame and a gear train, a circuit 80 breaker comprising a pair of supporting members secured to the frame, a pair of arms centrally pivoted to said supports by pin and slot connections, a member pivotally 85 connected to the inner ends of said arms, means for preventing the arms from moving in one direction past their substantially dead-center position, means controlled by the gear train for operating the outer end of one of said arms to move the arms out of said 90 position, spring means for shifting said arms and member after movement has been imparted thereto by said means, and switch means controlled by the outer end of the other arm. 95

Signed at Chicago, Illinois, this 23rd day of March, 1925.

FRANK J. FENCL.
